US00D628629S

(12) **United States Design Patent**
Liu

(10) **Patent No.:** **US D628,629 S**
(45) **Date of Patent:** **** Dec. 7, 2010**

(54) **COMBINATION PEN AND FLASHLIGHT**

(75) Inventor: **Liang Liu**, Ningbo (CN)

(73) Assignee: **Beifa Group Co., Ltd.**, Ningbo (CN)

(**) Term: **14 Years**

(21) Appl. No.: **29/353,488**

(22) Filed: **Jan. 8, 2010**

(30) **Foreign Application Priority Data**

Jul. 8, 2009 (CN) 2009 3 0192656

(51) **LOC (9) Cl.** **19-06**

(52) **U.S. Cl.** **D19/36**

(58) **Field of Classification Search** ..... D19/35, D19/36, 41, 42, 43, 44, 45, 46, 47, 48, 49, D19/50, 51, 54, 55, 56; 24/11 F, 11 P, 11 R; D26/49; 362/118, 206; 401/6, 52, 99, 100, 401/104, 105, 106, 107, 108, 109, 192, 195, 401/243, 244, 245, 246, 247; 708/107

See application file for complete search history.

(57) **CLAIM**

The ornamental design for a combination pen and flashlight, as shown and described.

DESCRIPTION

FIG. 1 is an upper front left perspective view of a combination pen and flashlight showing my new design;

FIG. 2 is a lower front left perspective view thereof;

FIG. 3 is a front elevation view thereof;

FIG. 4 is a left side elevation view thereof, with the right side elevation view being a mirror image of the left side elevation view;

FIG. 5 is a rear elevation view thereof;

FIG. 6 is an enlarged top plan view thereof; and,

FIG. 7 is an enlarged bottom plan view thereof.

1 Claim, 4 Drawing Sheets
